UNITED STATES PATENT OFFICE.

WEBSTER L. MARBLE, OF GLADSTONE, MICHIGAN.

FIREARM-SIGHT.

1,247,559.

Specification of Letters Patent. Patented Nov. 20, 1917.

Application filed June 26, 1916. Serial No. 105,877.

To all whom it may concern:

Be it known that I, WEBSTER L. MARBLE, a citizen of the United States, residing at Gladstone, county of Delta, and State of Michigan, have invented certain new and useful Improvements in Firearm-Sights, of which the following is a specification.

This invention relates to firearm sights. Any kind of a rear or peep sight is generally considered as an obstruction, encumbrance and unnecessary part in shot gun shooting but as indispensable in rifle shooting.

In "over and under" firearms which employ rifle and shot gun barrels arranged in superposed relation, the use of a rear or peep sight for the rifle barrel is considered indispensable, but such a sight constitutes an obstruction and an unnecessary part as far as the shot barrel is concerned. In this type of firearm if the rear sight is placed in the usual position on the upper barrel, it is in the way when using the shot barrel and if attached to the tang or neck of the stock, it interferes with the gripping of the gun in action.

One of the objects of the present invention is to provide a rear sight which may be exposed when the rifle barrel of an over and under gun is being used and can be concealed when not required for use as, for instance, when shooting the shot barrel, thereby overcoming the presence of the sight when it is not needed and preventing both the barrels and the neck or tang from being obstructed.

In its broadest aspect, my invention embodies a sight constructed and adapted to carry out the foregoing object. More particularly, the invention comprises an adjustable rear sight which can be elevated at the breech piece or block of the arm when required, or depressed and concealed within the breech piece or block when not needed.

The preferred embodiment of the invention is that which is set forth more fully hereinafter as illustrating one form which the invention may assume and in that embodiment I provide an improved adjusting and setting device for the sight which is controlled by novel means at the neck or tang, arranged so as not to interfere with the usual use of the arm at that point, by which a coin, knife-blade, or any suitable device may be employed for adjusting, the

elevation of the sight from point blank 55 range to any desired range. My improved adjusting means is adapted so that the sight will spring up to its former adjusted position at any time it is needed for use after it has been previously depressed and concealed. Improved means are also provided for the regulation of the sight to compensate for windage.

As the invention is susceptible of modification without departing from the essential 65 principles thereof, the following disclosure, and the showing in the drawings, is to be considered as illustrative, rather than restrictive, of the scope of the invention.

In the accompanying drawings:

Fig. 1 is a longitudinal section with certain parts in full lines, showing the invention;

Fig. 2, a section on line 2—2, Fig. 1;

Fig. 3, a view looking in the direction 75 of the arrow, Fig. 1, toward the breech piece or block, the hammers being removed and the frame broken away;

Fig. 4, a detail elevation of the sight taken on line 4—4, Fig. 1, showing the 80 frame in section;

Fig. 5, a detail front view of the sight alone;

Fig. 6, an edge view or side elevation thereof;

Fig. 7, a detail side elevation of the breech piece or block;

Fig. 8, a detail plan of the sight and the locking latch therefor;

Fig. 9, a side elevation of the firing pins;

Fig. 10, a diagrammatic showing of the firing pins through the breech piece looking toward the rear of the breech piece; and

Fig. 11, a detail plan of the tang portion 95 of the frame and the dial or head of the sight adjusting screw.

The frame is shown at 1 and the neck or tang at 2, 3 representing the fore-end. The upper rifle barrel 4 is disposed above the 100 shot barrel 5.

My improvements are illustrated in connection with an "over and under" firearm as the greatest usefulness of the sight exists in connection with a gun of that type where in it is desirable to project and adjust the sight when the rifle barrel 4 is used and to depress and conceal the sight when the shot

barrel 5 is to be used. The present improvements are particularly adapted for use in connection with an over and under firearm such as set forth in my Patent No. 5 1,223,411, dated April 24, 1917, for slide action firearms, but I do not limit myself to the use of the present improvements in connection with that particular firearm, as these improvements are susceptible of application to any over and under gun and, indeed, the sight need not necessarily be employed in connection with an over and under firearm, as it would have utility when used in connection with a single barreled arm.

The upper portion of the frame 1 is split vertically and receives the body 6 of a breech piece or block (Figs. 3 and 7), the block being secured by a screw-bolt 7 passing through an aperture 8 in the breech piece. The upper, rounded part 9 of the breech piece has shoulders 10 which overlie and rest flat upon the upper shoulders or edges 11 of the frame 1. The breech piece 20 has a tail, web or partition 12 which, as shown in Fig. 3, subdivides the open, upper part of the frame 1 into two hammer pockets or chambers 13, 14, the end 15 of said tail piece 12 entering a slot 16 in the frame 1, which holds it against flexing. The holes for the firing pins for the respective barrels 4, 5, are shown at 17 and 18.

The firing pins 19, 20, for the respective barrels 4, 5, lie loosely in the holes 17, 18, so that they may rebound, and hence, when the breech of the arm is closed, there will be no danger of premature explosion. After the gun is discharged, the hammers do not bear positively against the firing pins 19, 20.

40 The firing pins are each off-set both laterally and vertically, as shown diagrammatically in Fig. 10. The parts 19^a and 20^a are integral with the parts 19^b and 20^b, respectively. The object of the off-set firing pins 45 is to enable the respective hammers 21, of which the right-hand one appears in Fig. 1, to be provided side by side for the respective over and under barrels 4, 5, and to enable the hammers 21 to be exact duplicates in outline. The partition or tail piece 12 so spaces the hammers which lie in the respective chambers 13, 14, that either hammer may be grasped to cock the arm without liability of accidentally grasping both hammers, and 55 at the same time, the hammers are so closely associated that both of them may be readily simultaneously cocked, if desired, so that either barrel 4, 5, can be discharged first at the will of the operator.

60 The triggers 22, 23, are for the respective hammers 21. A trigger guard and pistol grip is shown at 24.

Projecting from the face of the breech piece is a lug 25 (Figs. 1, 4, 7) to which is 65 secured by a screw 26, the flat breech plate

27 which has apertures 28 to let through the points of the firing pins 19 and 20, said apertures being in line with the apertures 17 and 18. The breech end of the barrels 4, 5, close against the plate 27 when the arm is closed. 70

In the upper portion of the plate 27 is a transverse concavity 29 containing a bowed or leaf spring 30.

Slidable in an aperture 31 which extends through the head 9 of the breech piece, is 75 the shank or stem 32 of an internally screw-threaded tubular push button 33. A latch (Fig. 8) having a rectangular, open yoke or head 34 and a screw-threaded stem 35 which is screwed into the stem 32, is provided with 80 lugs 36 and is pressed rearwardly by the spring 30.

The sight bar or slide 37 (Figs. 1, 4, 5, 6) has a peep or sight opening 38 and shoulders 39 at its upper end. A slot 40 extends 85 longitudinally of the sight bar 37, and has its walls bearing against and guided by the side walls of the lug 25. The slide 37 moves up and down in a recess in the inner face of the breech piece.

The slot 40 permits the firing pins to project through the sight without interfering with them or with the movements of the sight, as shown in Figs. 1 and 4.

Elevation of the sight 37 is obtained by a 90 lever 41 pivoted at 42, pressed by a spring 43 and having a forked forward end 44 which receives the cross piece 45 at the lower end of the slide 37 and projects into the lower end of slot 40 and into the bifurcation 100 46 in the lower end of the slide 37. The joint affords a compensating connection between the lever 41 and the slide 37, minimizing friction, affording a secure joint, and permitting freedom of tilting movement for the slide 37 by adjusting the screws 47, 48 which are threaded through upper portions of the part 9 and bear on one side of the slide 37 to adjust the sight for windage, a bowed spring 48 bearing against the other side of the sight (Fig. 4).

An adjusting or distance screw 49 has its shank threaded through the tang 2 of the frame 1 and its head adapted to turn in a concavity 50. A friction spring 51 in the concavity 50 bears upon the head and prevents it from being accidentally turned. The lower end of the stem of the adjusting screw bears upon a widened portion 52 of the lever 41. The head of the screw 49 is provided with a dial 53 (Fig. 11). The slot 54, when in line with the zero mark 55 on the tang 2, indicates the point blank range of the sight which will then be, let us say, in the position shown in Fig. 1. The range distances on the scale 56 on the side of the sight slide 37 (Fig. 6) correspond with the numbers on the dial 53. The adjusting screw 49 being comparatively close to the pivotal point 42 of lever 41, a slight movement of the screw is

greatly multiplied in the resulting elevation or depression of the sight slide 37. In practice, the ratio is about eight to one. The head of the elevating screw 49 being practically flush with the tang 2, is entirely out of the way, not liable to be accidentally turned and does not interfere with the natural gripping of the neck of the stock in using the firearm. The slot 54 is of a size adapting it 5 to receive the point of a screw-driver, or a small coin, key, blade of a pocket knife, or other convenient means.

The tip of the screw 49 merely bears upon the part 52, and hence, while the screw will 10 remain where set, the sight slide 37 is free to be quickly pushed down when the shot barrel 5 is to be used, instead of the rifle barrel 4, and yet, when the lugs 36 of the yoke 34 are released from the shoulders 39, the 15 spring 43 immediately elevates the sight to the range to which it was previously adjusted.

When the sight is elevated, as in Fig. 1, for instance, the lugs 36 bear against the 20 flat face of the slide 37 and the adjustment of the screw 49 determines the range at which the slide is held by the spring 43. Adjustment of the screws 47, 48, provides for windage. When it is desired to use the 25 shot barrel 5, the upper portion 38 of the sight slide is pressed down by the finger, whereupon the lugs 36 are snapped into locked engagement with the shoulders 39 by the action of spring 30 on the yoke 34. The sight 30 then remains concealed until it is again needed, whereupon a slight pressure of the finger applied to the push button 33 of sleeve 32, releases the lugs 36 from the shoulders 39, the yoke then entering the slot 29, and the slide 37 is then snapped up by the spring 43 to the previously set range.

In Fig. 2, I have illustrated a sufficient portion of the slide action of the firearm set forth in my Patent No. 1,223,411, dated 45 April 24, 1917, to illustrate how the present improvements may be applied to that firearm. The frame 1 has an under-cut or substantially dove-tailed guide 57 which receives a correspondingly shaped foot-piece 50 58 on the receiver 59 which carries the barrels 4 and 5. The ejector or extractor 60 is guided by a pin 61 carried thereby and sliding in the receiver. The ejector strikes against the breech plate 27 when the firearm 55 is closed. At 62 there is shown the position of a dowel and socket which assists in holding the receiver rigid when closed.

Having thus described my invention, what I claim as new and desire to secure by Letters Patent, is:

1. In an "over and under" breech-loading firearm having a breech-piece, a rear sight movably mounted in the breech-piece for complete concealment therein or display 60 thereabove.

2. In an "over and under" breech-loading firearm having a breech-piece, a vertically slideable rear sight carried by said breech-piece and adapted for complete concealment therein or display thereabove. 70

3. A firearm provided with a rear sight arranged for display or concealment, spring means coacting therewith, and a releasable latch for holding said sight in concealed position. 75

4. A firearm provided with a spring-actuated rear sight arranged for display or concealment, a releasable latch for holding said sight in concealed position, and adjusting means for regulating the elevation which the 80 sight will assume when displayed.

5. A firearm provided with a spring-actuated rear sight arranged for display or concealment, a releasable latch for holding said sight in concealed position, and adjusting 85 means, operable when the sight is either displayed or concealed, for determining the elevation which the sight will assume when displayed.

6. A firearm provided with a movable 90 rear sight arranged for display or concealment, and adjusting means, operable when the sight is either displayed or concealed, for determining the elevation which the sight will assume when displayed. 95

7. An "over and under" firearm having a breech provided with a rear sight arranged at its breech for display or concealment in the breech, and spring means for projecting 100 said sight.

8. In a firearm having a breech, the combination with a rear sight carried by the breech thereof, of means, coöperating with said rear sight and adapted for moving it operable from the grip or neck of the stock 105 of the firearm.

9. In a firearm having a breech, the combination with a rear sight movable in the breech thereof, of operating means for said sight concealed within the frame of the firearm, and exposed adjusting means for said operating means. 110

10. In a firearm having a breech, the combination with a rear sight movable in the breech thereof, of operating means for said sight concealed within the frame of the firearm, and exposed adjusting means for said operating means arranged at the grip or neck of the firearm stock. 115

11. In a firearm having a breech, the combination with a rear sight movable in the breech thereof, adapted for display or concealment, of spring-actuated operating means for raising said sight, and a combined stop and adjusting device coöperating with said 120 spring-actuated operating means.

12. In a firearm having a breech, the combination with a rear sight slideable up and down within the breech thereof adapted for display or concealment within said breech, 125

- of a spring-actuated lever adapted to raise said sight, and a stop for limiting the movement of the lever.
13. In a firearm having a breech, the combination with a rear sight slidable up and down within the breech thereof adapted for display or concealment within said breech, of a spring-actuated lever adapted to raise said sight, a releasable latch for holding the sight in concealed position, and a stop for limiting the movement of the lever.
14. In a firearm having a breech, the combination with a rear sight slidable up and down within the breech thereof adapted for display or concealment within said breech, of a spring-actuated lever adapted to raise said sight, and a combined stop and sight-adjusting screw disposed at the grip or neck of the firearm.
15. In an "over and under" firearm having a breech, the combination with a rear sight movable in the breech thereof, of exposed adjusting means for said sight.
16. In an "over and under" firearm having a breech, the combination with a rear sight adapted for display or for complete concealment in the breech thereof, a spring for raising said sight and a latch for holding said sight down when the latter is depressed.
17. In an "over and under" firearm having a breech, the combination with a spring-raised rear sight adapted for display or for concealment in the breech thereof, a latch for holding said sight down when the latter is depressed, and combined sight-adjusting and stop means exposed for operation.
18. In an "over and under" firearm having a breech, the combination with a movable rear sight adapted to be raised or to be completely concealed within the breech thereof, of means for adjusting said sight for windage, and other means for adjusting the elevation of the sight.

In testimony whereof, I hereunto affix my signature.

WEBSTER L. MARBLE.
